Frank A. Neuman,
ATTORNEY.

UNITED STATES PATENT OFFICE.

NORMAN M. COTRELL, OF CHICAGO, ILLINOIS.

FOUNTAIN BRUSH.

Application filed November 13, 1926. Serial No. 148,249.

This invention relates to cloth brushes and particularly to means whereby a liquid detergent may be delivered to the bristles of a brush for the purpose of increasing the 5 cleansing action and effectiveness of the brush.

It is an object of this invention to provide a holder for fluid, such as gasoline or other cleansing compound or fluid, which 10 will flow through the head of the brush and be delivered to the bristles thereof in such quantities as will prove desirable, the said invention including novel means for controlling the delivery of the cleaning 15 fluid to the brush.

It is furthermore an object of the invention to provide a brush having a reservoir or magazine for containing the cleansing agent and to associate therewith novel 20 means for controlling the flow of the cleansing fluid from the container to the brush and the said invention further contemplates the provision of novel means whereby the controlling instrumentality may be shielded or 25 guarded in order that it will not interfere with the manipulation of the brush or prove unsightly.

With the foregoing and other objects in view, the invention consists in the details 30 of construction, and in the arrangement and combination of parts to be hereinafter more fully set forth and claimed.

In describing the invention in detail, reference will be had to the accompanying 35 drawings forming part of this application, wherein like characters denote corresponding parts in the several views, in which—

Figure 1 illustrates a sectional view of 40 a brush and its attachment, embodying the invention; and

Figure 2 illustrates a detail view of the controlling device in association with its seat.

In these drawings 5 denotes the head of 45 a brush and 6 the tufts of bristles which have their ends seated in the head of the brush as is ordinarily done in the manufacture of brushes that are of the wire drawn type.

It is intended to supply cleansing fluid, 50 such as gasoline or the like to the area of the device above the head of the brush and as gasoline is of a penetrative character it will find its way between the bristles in the head and the said gasoline will enter the tufts of the brush and its presence will in-

crease the effectiveness of the brush when it is manipulated. If desired, the head of the brush may be provided with perforations through which gasoline may escape, but it 60 has been found in practice that the arrangement first described will prove satisfactory and efficient.

The brush is associated with a reservoir having a shell or casing 7 which is preferably 65 curved and internally near the lower edge of the shell or reservoir, a shoulder 8 is formed against which is seated and secured a wall or partition 9 which serves to confine the fluid in the reservoir under certain conditions as will presently be explained.

A flange 10 constituting an extension of the shell, in the present embodiment of the invention, is provided, although this construction may be modified to suit particular 75 requirements and the said flange is of a shape to embrace the edge of the head of the brush and the said head is seated and secured therein by any appropriate packing 11. There is preferably a space 12 between 80 the inner surface of the brush and the outer surface of the partition or wall 8 and this space constitutes a clearance for the passage of gasoline over the inner surface of the brush in order that it will be distributed 85 evenly with respect to the tufts of the brush.

The inner surface of the wall or partition 8 is preferably provided with a boss or metallic deposit 13 and an aperture 14 is formed therein which extends through 90 the wall or partition to permit the flow of the cleansing agent from the reservoir to the space 12. A valve seat is formed in the aperture of the boss and a tapered valve 15 coacts with the valve seat for closing the 95 passage and the valve will of course be unseated when fluid is to be delivered to the brush.

The aperture 14 is diagonally disposed as 100 shown and the valve is mounted for movement into and out of the seat. In the present embodiment of the invention, the valve is formed as a part of a screw 16 which is threaded in a bushing 17 secured in an aperture 18 of the shell 7. The head 19 of the 105 valve screw is preferably knurled in order that it may be expeditiously manipulated and the said valve screw has an aperture 20 through it which acts as a vent for admitting air to the reservoir when fluid is flowing therefrom. A gasket 21 of suitable material is interposed between the head of the

valve screw and the brush and any suitable material may be employed for this gasket that will serve to create a leak-proof joint.

The shell has an inturned flange 22 and in producing the flange, the shell is shaped to form a seat in which the head of the valve screw is almost wholly embedded so that it does not project to an extent which will interfere with the manipulation of the brush or the appearance of the device as a whole.

It will be apparent to those skilled in the art that any appropriate joints may be formed between the partition 8 and the shell

and that the valve seat may be made of any appropriate material or metal which will withstand wear and insure proper seating of the valve.

The base or partition of the tank should be of a relatively heavy material to prevent bulging when under pressure of the valve while a layer of solder or other soft metal is used to yield slightly where the valve is seated to make an absolutely tight and gasoline prevention leakage at the bottom. In other words, if there should be a slight variation in the diameter of the tapered pin 15, this soft metal will yield to the true shape of the pin itself, making an absolutely tight nesting fit. In manufacture, the wood block of the brush will be vulcanized in the bottom of the shell by hot rubber to prevent any leakage around the edges of the brush, forcing all gasoline to escape through the bristles, an essential of this improved method of cleaning. Also the gasket 27 that fits underneath the head of the plunger to prevent leakage between the threads will be of rubber of special composition, resistant to gasoline.

I claim—

1. In a fountain brush, a shell having an aperture the said shell being indented and provided with an inwardly extending flange around the aperture, a threaded bushing in the aperture, an externally threaded valve in the bushing, an apertured partition in the shell, said partition having a valve seat at the aperture adapted to coat with the aforesaid valve, a brush head having tufts of bristles through which fluid may penetrate, and means for securing the head of the brush in the shell in close proximity to the partition.

2. In a fountain brush, a shell having an aperture, a bushing secured in the aperture, a valve threaded in the bushing, said valve having an air passage therethrough, an apertured partition internally of the shell, a shoulder having a valve seat in alignment with said valve and the aperture of the partition, a flange forming a part of the shell, and a brush head secured in the flange in spaced relation to the partition.

3. In a fountain brush, a reservoir consisting of a cupped shell having a rounded peripheral portion, said portion being provided with a concavity, said concaved portion having an aperture therein, a threaded bushing in said aperture, a valve threaded in the bushing having an air passage therethrough, a wall in the shell forming a compartment, said wall having an aperture and a valve seat alining therewith with which the valve coats, and a brush having a head secured in the shell in position to receive fluid from the reservoir through the aperture in the partition.

NORMAN M. COTTERELL.
